UNITED STATES PATENT OFFICE.

CHAMPION H. JUDSON, OF DOBBS FERRY, NEW YORK.

INTERNAL-COMBUSTION ENGINE.

1,109,681.

Specification of Letters Patent. Patented Sept. 8, 1914.

Application filed August 19, 1910. Serial No. 578,013.

To all whom it may concern:

Be it known that I, CHAMPION H. JUDSON, a citizen of the United States, residing at Dobbs Ferry, in the county of Westchester, in the State of New York, have invented certain new and useful Improvements in Internal-Combustion Engines, of which the following is a specification.

My invention relates generally to internal combustion engines and specifically to two-cycle engines, that is, engines having an impulse stroke every revolution, but features thereof are adapted to be applied also to internal combustion motors having a different cycle of operation, such, for example, as the well-known four-cycle motor.

My invention includes improved valve mechanism of manifold advantages, and also novel methods of scavenging or ridding the cylinder of the burnt gases remaining therein at the conclusion of the power stroke.

In the accompanying drawings which form a part of this specification, Figure 1 is a sectional elevation of a four-cylinder engine of my improved type; Fig. 2 is a side elevation looking at the left-hand end of Fig. 1; Fig. 3 is a transverse section on line III—III of Fig. 1; Fig. 4 is a section, parts being shown in full, on line IV—IV of Fig. 1; Fig. 5 is a sectional view similar to Fig. 1, showing a modification, while Figs. 6 and 7 are sections taken on lines VI and VII, respectively, of Fig. 5; Fig. 8 is a view similar to Fig. 1, illustrating a modification; Fig. 9 is a transverse sectional view taken on line IX—IX of Fig. 8; Fig. 10 is a sectional view taken on line X—X of Fig. 8; Fig. 11 is a longitudinal sectional view of the bevelled gear shown in plan view in Fig. 9.

Referring in detail to the drawings illustrative of the form shown in Fig. 1, the numeral 1 designates a base on which are mounted the cylinders 2 in which reciprocate the pistons 3. Connecting the pistons with the crank shaft 4 are the connecting rods 5. Upon the end of the crank shaft are mounted the fly-wheel 6 and adjacent to it the bevel gear 7 meshing with a similar gear 8 on the sleeve 9 which has at its upper extremity the collar 10. This collar and the gear 8 are so disposed with reference to the bearing block of the sleeve supported upon the frame of the structure that the sleeve is free to rotate, but is prevented from moving in a vertical direction. Within the sleeve is the vertical shaft 11, a pin 12 upon which

passes through the oblique slot 13 in the sleeve. At the upper end of the shaft is located a sleeve 9 having an oblique slot 15 in which the pin 14 enters, the sleeve 9 having a collar 16 facing that of the lower sleeve but being otherwise disposed in the bearing block 17 in a manner similar to that of the lower sleeve 9. The slot 15 has an inclination reverse to that of the slot 13. Carried upon the upper end of the sleeve 16 is the bevel gear 18 meshing with a similar gear 19 upon the horizontal tubular valve structure 20. Intermediately disposed upon the shaft 11 with respect to the two sleeves 60 is the grooved member 21, entering the groove in which are the claws 22 of the bell crank lever 23, which is pivoted to the main frame at the point 24. The valve mechanism includes a horizontal tubular member 65 20 having ports 25 adapted to register with ports 26 in the top of the cylinders, this tubular structure being rotated by the gears 18 and 19 from the shaft 11. Carried upon one end of the valve mechanism is the distributor 27 of the ignition system having the 70 four contacts 28 disposed at intervals of 90 degrees about the circumference of the stationary ring 29 and contacting with the brush 30 carried on the end of the tubular 75 structure 20. Wires 31 lead to the spark plugs 32 in the cylinder heads and provide means for igniting the explosive mixture in the manner usual in internal combustion engines. By operating the lever 23 the shaft 80 11 may be moved in a vertical direction, and by virtue of the action of the pins 12 and 14 in their reversely inclined slots 13 and 15, the angular relation of the gears 8 and 18 may be varied at will, thereby altering 85 the time at which the ports 25 will register with the ports 26 and permit the charge to enter the cylinders, at the same time varying the time at which the explosions in the cylinders will occur. At the end of the tubular 90 valve opposite to that upon which is mounted the distributing system, I preferably place a blower 33 which may be of the centrifugal or any other well-known type. The supply pipe 34 of this blower leads from 95 the carburetor 35 and the explosive mixture is therefore taken from the carburetor and forced under pressure into the tubular valve 20, being admitted to the cylinders in rotation at the times when the ports 25 register 100 with the ports 26. Formed about midway in the cylinders are the exhaust ports 36.

leading to the exhaust manifold 37. The cylinders may be provided with water jackets 38 for the purpose of keeping the temperature of the cylinders at a workable point.

In the operation of my device, the cycle is as follows: Considering the explosion of the previous stroke to have taken place and the piston forced down to the point where it has commenced to uncover the exhaust ports, the spent gases, being at a pressure much greater than atmospheric, will rush into the ports and out through the exhaust manifold as soon as the ports are uncovered. Before the ports are completely opened, rotation of the tubular valve brings the inlet ports 25 opposite to the cylinder ports 26 and the explosive mixture under pressure is forced into the top of the cylinder, thereby aiding in scavenging the cylinder of the spent gases of the previous stroke. As the piston starts on its upward or compression stroke, it early closes the exhaust ports, and then the tubular valve, having by this time rotated so that the inlet ports no longer register with the ports in the top of the cylinders, the explosive mixture is confined in the cylinder and compressed by the continued travel of the piston. The distributor causes a spark to ignite the mixture just before the piston reaches the top of its stroke. The angularity of the firing mechanism and of the inlet valve with respect to the crank shaft is made variable to allow an earlier firing and an earlier inlet of the firing charge in order to effect the most economical operation at high speeds.

Now referring in detail to the modification illustrated in Figs. 5, 6 and 7, the means for injecting the charge under compression in this modification comprise a centrifugal blower 39, or other suitable means for compressing air, which may be belt-driven from the pulley 40 on one end of the crank shaft. The outlet pipe 41 from this blower has two branches, 42 and 43. The branch 42 leads, by means of a manifold 44, to the small inlet ports 45 in the cylinder opposite the exhaust port 36^a. The inlet port 45 I preferably make of less area than the exhaust port, the bottom of the inlet port being upon the level of the bottom of the exhaust port, and the top of the inlet port being below the level of the top of the exhaust port, and preferably at about half its height; these dimensions need not, however, be strictly adhered to. The second branch of the outlet pipe from the blower leads to a jet 46 which discharges into the cylindrical chamber 47. Tapping one side of this chamber is the discharge pipe 48 from the carbureter 35^a. In the modification illustrated in Fig. 5 I have shown the lower portion of the vertical shaft 11 as square, as indicated at 49, and engaging a correspondingly shaped socket in the

sleeve 9^a, in place of the pin and slot mechanism shown in Fig. 1. In other respects the mechanism of Fig. 5 is similar to that of Fig. 1.

The operation of the motor of Fig. 5 differs from that of the form first described in that air pressure is forced by the blower 39 through the jet 46 which is centrally disposed with relation to the end of the tubular inlet valve 20, and there picks up sufficient hydrocarbon vapor supplied by the carbureter, to form the proper explosive mixture, which is carried into the tubular inlet valve still under pressure. The cycle of operation is as follows: Supposing the piston to have reached nearly the end of its stroke and to be just uncovering the exhaust port, the cylinder will then be filled with burnt gases remaining from the power stroke, and, as soon as the exhaust port is uncovered these gases, being under high pressure, will rush therethrough. An instant after the piston uncovers the exhaust port it will also uncover the small port 45 opposite thereto and will permit a current of air under pressure to pass into the cylinder. At practically the same instant that the exhaust port first opened, the inlet port at the top of the cylinder also opened and the explosive mixture under pressure entered the cylinder. The function of the current of air from the air port 45 is to aid in creating a circulation which will help to rid the cylinder of the spent gases remaining after the power stroke, and also to cool, to some extent, the interior of the cylinder, although not to a degree which will prevent efficient and economical operation. As the longitudinal length of the air port is small, the piston closes it soon after starting on its up stroke, and therefore, as the current of air is cut off early in the stroke, the explosive mixture is not diluted to an appreciable degree, and the scavenging of the cylinder is accomplished in this manner without affecting the efficient operation of the motor through the waste of the hydrocarbon.

The modification illustrated in Figs. 8 to 11, inclusive, is similar in construction to the engine shown in Fig. 1 with the exception of the means for altering the angularity of the valve mechanism with respect to the crank shaft and the method of mounting the tubular valve mechanism on the frame of the engine. Referring to these figures, the numeral 50 designates the flywheel mounted on the end of the crank shaft, to the other extremity of which is keyed the beveled gear 51 meshing with the gear 52 having the two bearing surfaces 53 and 54, adjacent to which are the collar portions 56 and 57. This gear is mounted in a bracket 58 attached to the main frame of the engine and having the two bearings 59 and 1

60 adapted to straddle the gear 52, and through lateral engagement with the collars of the gear to permit rotation of the same, but to prevent longitudinal translation.

5 Within the gear 52 is the square shaft 61, which is twisted equally on each side of the center in the same horizontal direction, the internal surface 62 of the gear 52 being given the same pitch as the twisted shaft, 10 being cut to conform closely to the latter. The shaft passes through a hole 63 in the bracket 58 and through a bracket 64 similar to the bracket 58, there engaging a symmetrically disposed gear 65 similar to the gear 52. The gear 65 meshes with the gear 19 keyed to one end of the tubular valve structure 20. The upper end of the shaft 61 terminates in a grooved bearing member 66 which is engaged by the jaws 67 carried on 20 one end of the bell-crank lever 68, which is pivoted at the point 69 to a standard 70 affixed to the main frame. To the other extremity 71 of the bell-crank lever is pivoted a link 72 which may be extended to the portion 25 of the engine where the controlling mechanism is grouped. By operating the bell crank lever through the agency of this link, the shaft 61 will be translated longitudinally, and owing to the twist which it has, the gears 65 and 52 will change their relative angularity, and by this method the relative angularity of the tubular valve structure and the crank shaft may be altered at will within such limits as may be desired 30 in the efficient operation of the engine. In Figs. 8 and 10 is also illustrated an improved method of mounting the tubular valve structure in such manner that it may be readily removed for purposes of cleaning 35 or repair. At the upper end of the cylinder is formed a seat 73 which is in the same horizontal plane with the center of the tubular valve structure. The latter is held in place by a cap plate 74 which may extend 40 the entire length of the engine and be bolted to the seat 73 by the stud bolts or other means 75. By the removal of these bolts the cap plate may be lifted off and the tubular valve structure removed without tearing down any of the other portions of the 50 engine.

Having thus described my invention, I claim:

1. An internal combustion engine having 55 a crank shaft, a functioning valve and driving connection between said crank shaft and valve including a plurality of blocks and a twisted shaft passing through said blocks and adapted to fit the same for altering the 60 point in the stroke at which the valve shall open and close.

2. An internal combustion engine having an explosion chamber, a piston therein actuating a crank shaft, a valve at the head end 65 of said explosion chamber, and means for

altering the point in the stroke at which the valve shall open and close, including a plurality of blocks, a twisted shaft passing through said blocks and fitting the same, means for positively rotating one of said 70 blocks from the crank shaft and means for transmitting motion from the other to said valve.

3. An internal combustion engine having an explosion chamber, a piston therein actuating a crank shaft, a rotary tubular valve at the head end of the explosion chamber, and means for altering the angularity of said valve with respect to said crank shaft, including a plurality of blocks, a twisted shaft 75 80 passing through said blocks and fitting the same, means for positively rotating one of said blocks from the crank shaft, and means for transmitting rotation from the other to said valve. 85

4. An internal combustion engine having an explosion chamber, a piston therein actuating a crank shaft, a rotary tubular valve at the head end of the explosion chamber, and means for altering the angularity of 90 said valve with respect to said crank shaft, including a plurality of blocks, a twisted shaft passing through said blocks and adapted to fit the same, means for positively rotating one of said blocks from the crank shaft, 95 means for transmitting rotation from the other to said valve, and means for adjusting said twisted shaft in a longitudinal direction.

5. An internal combustion engine having 100 an explosion chamber, a piston therein actuating a crank shaft, a rotary tubular valve at the head end of the explosion chamber, and means for altering the angularity of said valve with respect to said crank shaft, including a block rotated from said crank shaft aligned with a block rotating said valve and a twisted shaft passing through said blocks and fitting the same, and means for adjusting 105 said shaft longitudinally while the engine is in operation. 110

6. In combination, in an internal combustion engine, a carbureter, an explosion chamber, an exhaust port therein and means for supplying the explosive mixture to the explosion chamber at a higher pressure than exists in the explosion chamber shortly after the opening of said exhaust port, including a blower and a rotary tubular inlet valve at the head end of said explosion chamber, and 115 means for varying the point in the cycle at which the mixture is admitted to the explosion chamber. 120

7. In combination, in an internal combustion engine, a carbureter, an explosion chamber, an exhaust port therein and means for supplying the explosive mixture to the explosion chamber at a higher pressure than exists in the explosion chamber shortly after the opening of the exhaust port, including 125 130

a blower, and a rotary tubular inlet valve at the head of said explosion chamber, and means for varying the point in the cycle at which the mixture is admitted to the explosion chamber while the engine is in operation.

In testimony whereof I have signed my

name to the foregoing specification in the presence of two subscribing witnesses this 16th day of August, 1910.

CHAMPION H. JUDSON.
